UNITED STATES PATENT OFFICE.

DWIGHT TRACY, OF NEW YORK, N. Y., ASSIGNOR TO OLIVER H. HARRIS,
OF WORCESTER, MASSACHUSETTS.

SWITCH-STAND.

SPECIFICATION forming part of Letters Patent No. 378,025, dated February 14, 1888.

Application filed September 3, 1886. Serial No. 212,591. (No model.)

To all whom it may concern:

Be it known that I, DWIGHT TRACY, of the city and county of New York, in the State of New York, have invented a new and useful Improvement in Switch-Stands, of which the following is a specification.

My invention relates to safety-switch stands which are so constructed that the switch-rail is held against movement by a yielding resistance which is sufficient to prevent the switch from being surreptitiously shifted, but which will yield and permit the switch to be shifted by the wheels of a train in case it be wrongly set.

Important objects of my invention are to provide a safety-switch stand of very simple and inexpensive construction; also, to provide a safety-switch stand which may also be used in connection with a stub-switch to hold the rails immovable, thereby enabling railways, in case it becomes necessary to order a stand for a stub-switch which is not worn out, to obtain a stand which may be used for the stub-switch until the latter is worn out, and may be used with a safety-switch when it is substituted for the stub-switch; also, to provide a secure and simple connection between a switch-operating rod and a switch-rail.

The invention consists in novel combinations of parts hereinafter described, and pointed out in the claims.

In the accompanying drawings, Figure 1 is a vertical section of a switch-stand embodying my invention, which is constructed for support on two ties, and which may be used for either a safety-switch or a stub-switch. Fig. 2 is a plan of the upper portion thereof. Fig. 2* is a horizontal section on the plane of the dotted line xx , Fig. 1. Fig. 3 is an elevation of the upper portion of the stand, showing the operating-handle as locked in a position to render the stand capable of use as a safety-switch stand. Fig. 4 is an elevation of the upper part of the stand in a plane at right angles to Fig. 3. Fig. 5 is an elevation similar to Fig. 4, but showing the operating-handle as locked for a stub-switch. Fig. 5* is an elevation and partial section on the plane of the dotted line **, Fig. 3, showing more clearly the means for locking the operating-handle. Fig. 6 is a horizontal section on the plane of the

dotted line yy , Fig. 1, showing a safety-switch rail connected with the operating crank and a stub switch rail and rod unconnected with the crank. Fig. 7 is a plan of the crank alone. 55 Fig. 8 is a sectional view of a switch-rail and a rod connected therewith according to my invention. Fig. 9 is a vertical section of a safety-switch stand also embodying my invention and constructed for support on a single tie. Fig. 60 10 is a plan of a safety-switch rail and a horizontal section of a safety-switch stand of modified form, but also embodying my invention. Fig. 11 is a vertical section on the plane of the dotted line zz , Fig. 10. Fig. 12 is an elevation 65 of the stand shown in Figs. 10 and 11; and Fig. 13 is a sectional view thereof on the plane of the dotted line 11 , Fig. 10.

Similar letters of reference designate corresponding parts in all the figures.

Referring first to Figs. 1 to 8, inclusive, A designates the frame or casing of the stand, which is of plain cylindric form, with lateral base projections or foot portions A' extending in opposite directions and adapted to be supported on two ties, B. This may be of cast metal.

C designates the switch-operating shaft, carrying at its lower end a crank, C', with which the switch-operating rod D is connected. One 80 end of this rod D is connected with the crank and the other end is connected, as shown in Fig. 6, with the safety-rail E. The switch-operating shaft is surrounded by a sleeve, F, having at the upper end a head, F', which fits 85 a cylindric bearing, a, in the upper portion of the stand A, and having at the lower end a cam, F'', the purpose of which will be herein-after described. The shaft C is supported at its lower end in a bearing, a', formed in the 90 bottom of the stand A, and is afforded suitable bearing in the sleeve and head F F', the latter being held concentric with the stand by fitting the bearing a. Upon the upper end of the shaft C is secured a head or collar, C'', which may be held against turning by means of a cross-pin, b, or other means, and in which is pivoted at b' the operating-lever C'. The portion of the head F' which overlaps the stand A has formed in it a series of notches, 95 100 c, which, as shown in Fig. 2, are at equidistant points around the circumference.

It will be from the above description readily understood that when the operating-lever C³ is turned downward, so as to engage with one of the notches c, as shown in Figs. 3 and 4, the shaft C and the sleeve F will be locked together, so that neither can turn independent of the other; but both may be turned together within the stand. When the lever C³ is raised into a horizontal position, so as to disengage it from the notch c, the shaft C and the crank may be turned freely independent of the sleeve and head F F'. When the operating handle or lever C³ is turned downward into engagement with one of the notches c, it may be locked in that position by any suitable means, and when locked in that position the handle C³ lies so close to the side of the stand A, as shown in Fig. 3, that there is no opportunity for the introduction of a bar between them in order to turn the shaft and sleeve C F surreptitiously.

As a means of locking the handle C³, I have represented a key, d, which consists of a flat plate notched at its lower edge, as shown at d' in Fig. 5*. This key is free to slide in a mortise or slideway, d'', formed in the head C² just back of the upper end of the handle C³, which projects somewhat above its pivot b'. The key d is free to slide lengthwise, its motion being limited by shoulders d³, and near one end it is perforated at d⁴, to receive a padlock, d⁵. When the lock is removed, the key can be slid endwise sufficiently to bring the notch d' coincident with the handle C³, and the latter may then be swung upward into a horizontal position. To lock the handle, the key is pulled back until it obtrudes itself in the way of the handle C³, and is locked by passing the padlock through the eye d⁴.

In order to afford a yielding resistance to the turning of the shaft C and the sleeve F when they are locked together, I have represented a yoke, G, which is arranged horizontally and receives the shaft C and the lower end of the sleeve loosely through it, and which also has a shoulder and bearing-surface, e, which engages with the cam F². The yoke G is guided by a rod, G', which is fixed to it and extends through a bearing, e', in the lower portion of the stand A, as shown in Figs. 1 and 6, and this guiding-rod G' is surrounded by springs G², which bear at one end against the interior of the stand and at the other end against the end of the yoke G.

As shown in Fig. 6, the cam F² is square or rectangular in its outline, and when one of these square sides bears against the shoulder e the latter acts by the force of the spring G² to hold the cam, together with the sleeve F and the shaft C locked thereto, against turning. If, however, a sufficient force be applied through the switch-operating rod D, as would be produced by the wheels of a train acting on the rail E in case it be wrongly set, the shoulder or engaging device e will yield to the action of the cam by reason of the compression of the spring G², and will permit the shaft C and cam

and sleeve F² F to turn, so as to bring another side of the cam against the shoulder or engaging device e. From Fig. 6 it will be seen that if anything more than one-eighth of a rotation is made the shoulder or engaging device e will come nearly opposite another face of the cam F², and will, by the pressure of the spring G², act automatically to complete the turning of the cam and shaft C.

Safety-switches which will be automatically shifted by the action of the wheels of a train in case they are wrongly set are becoming more and more popular on railways, and in some States legislative enactments have been made compelling railways to replace worn-out switches with safety-switches in all cases. Sometimes a railway will be obliged to replace a switch stand before the switch itself is worn out; and one object of my invention has been to provide a stand which could be used with a stub-switch, and which, when the stub-switch is worn out and replaced with a safety-switch, could also be used with equal facility with a safety-switch. The stub-switch requires a greater throw than the safety-switch, and to enable the stand to be used with either switch I make the crank C' with two holes, **, at different distances from its center, as shown in Fig. 7, and with either of which the switch-operating rod may be connected. When the switch stand is to be employed for a safety-switch, the rod should be connected with the hole nearest the center, making the crank of shortest length, and if it is to be used for a stub-switch the crank should be connected with the hole farthest from the center, making a longer crank. In Fig. 6 I have shown a stub-switch rail, E', and its operating-rod D', which may be connected with the crank C'.

When the switch-stand is to be used with a stub-switch, the shaft and cam C F² should be locked fast to the stand, so that they cannot turn relatively thereto; and to enable the stand to be so used I have represented upon the side of the stand A notched lugs or ears f, which are set at right angles to each other, and one of which is represented in Fig. 5, while both are shown in Fig. 2*. If the shaft C is turned so that the operating-handle C³, when swung downward, will engage not only with the notch c in the sleeve-head F', but also with one of the notched lugs f, the shaft C will be locked immovably with the stand, so as to hold a stub-switch.

In Figs. 6 and 8 I have represented a very strong connection which may be made between the operating-rod D' and a stub-switch rail, E', and which will enable the rod to assume different angles relatively to the rail. The rod D' has at the end a yoke, D², which extends under the base of the rail E', and has at the top overhanging lips or flanges d⁶, which engage with a circular block, d', which is divided so as to fit opposite sides of the rail, and is flanged to engage with the overhanging lips d⁶. The device is locked to the rail by means of a key, d', driven in between the web of the

5 rail and one section of the block d' , and a firm connection is thus produced between the rod D' and the rail E', which will also permit of the rod D' being swung at different angles relatively to the rail, the overhanging lips d' turning on the flanged block d' .

10 The switch-stand shown in Fig. 9 differs from that previously described only in having a single base projection or foot portion, A', whereby it is supported upon a single tie, B, and in being adapted for use only in connection with a safety-switch. The crank C' for this stand is of a single length, and is connected with the switch-operating rod D at an 15 invariable distance from the center of the shaft C. The construction and arrangement of the sleeve F, with its head and cam F' F'', are the same as before described, and the operating-handle C' may be swung into a horizontal position, as shown in Fig. 9, in order to free the 20 shaft from the sleeve and cam and enable the switch to be set by hand, or may be swung downward into engagement with one of the series of notches c in the head F' of the sleeve F. 25 It is advantageous to have a number of notches at equidistant points in the sleeve-head F', because then, after the switch is set automatically by a train, it is only necessary to turn the shaft back one-quarter of a revolution in each instance in order to set it by 30 hand, and automatically the sleeve F, with its head F' and cam F'', will be advanced step by step continuously in one direction around the shaft C.

35 Referring now to the switch-stand shown in Figs. 10 to 13, inclusive, which represent a ground-lever stand, A designates the frame or casing wherein the parts are secured, and which is adapted to be bolted to a tie, B. F 40 designates a sleeve which extends transversely through and is fitted to bearings in opposite sides of the frame or casing A, and has formed upon it a cam, F'', represented in Fig. 11 as being triangular or having three faces and a head, F', which overlaps said frame or casing A. The shaft C extends axially through and is journaled in the sleeve F, and has at one 45 end a head, C', which is provided with a lateral projection forming a crank, C', with which 50 the switch-operating rod D is connected, as best shown in Figs. 10 and 12.

The operating-handle C' is pivoted at b' in the head C', and may be swung so as to project radially from the head, as shown by dotted lines in Fig. 13, or so as to project parallel with the axis of the head, as shown by full lines in Figs. 10 and 13. In the latter position, the end of the handle C' engages with one of several notches c in the head F', which correspond with the three sides of the cam F''. The cam is acted upon by a yielding engaging device, e, which has projecting from it a stem, G', fitting a bearing, e', in the frame or casing A, and surrounded by a spiral spring, G'', which 65 holds the engaging device e against the face of the cam F''. In order to hold the engaging device e from dropping down out of engage-

ment with the cam, it is provided with ears or projections e*, which extend forward over cylindric bearing-surfaces c' upon the sleeve 70 F, and which hold the engaging device e in position both laterally and vertically.

When the operating-handle C' is swung into a radial position relative to the shaft C, as shown by dotted lines in Fig. 13, its end is disengaged from the notches c and the shaft C may be readily turned to shift the switch-rail E by hand. When the operating-handle C' is swung into a position parallel with the shaft C, as shown in Fig. 10 and in full lines in Fig. 80 13, its end engages with the notch c, and so locks the cam F'' and the shaft C together, that neither can be turned independent of the other, but both will be held against turning by the yielding resistance offered by the engaging 85 device e.

What I claim as my invention, and desire to secure by Letters Patent, is—

1. The combination, with a switch-stand, a crank-shaft and crank, and an operating-handle, of a sleeve loosely surrounding the shaft, and which has no connection with the shaft save through the operating-handle, and engaging devices between the sleeve and stand, one of which is arranged to yield in a direction 95 transverse to the shaft to the action of the other, substantially as herein described.

2. The combination, with a switch-stand, a crank-shaft and crank, and an operating-handle, of a sleeve surrounding the shaft and provided with a cam or engaging device, a yielding spring-actuated device on the stand, and a notched head or flange on the sleeve, with which the operating-handle may engage to connect the shaft and sleeve, substantially as 105 herein described.

3. The combination, with a switch-stand, a crank-shaft and crank, and an operating-handle, of a sleeve surrounding the shaft and provided at one end with a notched head, with 110 which the operating-handle may engage to connect the shaft and sleeve, and provided at the other end with a cam, and a yielding spring-actuated engaging device arranged to move transversely to the shaft and acting 115 upon the cam, substantially as herein described.

4. The combination, with the switch-stand, the crank-shaft and its pivoted operating-handle, of a sleeve surrounding the shaft and 120 provided with a notched head and a cam, and a spring-actuated yoke receiving the shaft through it and having a shoulder bearing against said cam, substantially as herein described.

5. The combination, with a switch-stand and a crank-shaft provided at one end with a crank and at that end fitting a bearing in the stand and provided at the other end with a pivoted operating-handle, of the sleeve F, fitting a bearing in the top of the stand and there provided with a notched head for the engagement of the operating-handle, and provided with a cam, F'', and the spring-actuated 130

yoke and guide rod G G', forming a yielding engaging device, substantially as herein described.

6. As a new article, the switch stand herein described, having a crank-shaft the crank of which is constructed for attachment of a switch-operating rod at different distances from its center, an operating-handle pivoted so as to swing in a vertical plane, a yielding lock for opposing a yielding resistance to the turning of the shaft when operated with a split or point switch, and a positive lock for holding the shaft positively against turning when operated in connection with a stub - switch, substantially as herein described.

7. The combination, with the stand, crank-shaft, and yielding engaging devices of a safety-switch stand, of an operating-handle pivoted to swing in a plane parallel with the shaft and closing against the stand when swung into its locked position, and locking devices for holding the handle in such locked position, so that a lever or bar cannot be introduced between the handle and stand for turning the shaft, substantially as herein described.

8. The combination, with a switch stand, a crank-shaft, and pivoted operating-handle, of a sleeve surrounding the shaft and provided with a head in which are notches for the engagement of the operating-handle at equidistant points around its circumference, and also provided with a cam, and a spring-actuated engaging device arranged upon the frame and acting upon said cam, substantially as herein described.

9. The combination, with the crank-shaft of a safety-switch stand, provided at the end with a head wherein is pivoted an operating-handle, of a locking-key fitted to a slideway in said head and notched to permit the swinging of the handle when the key is adjusted to proper position, but not otherwise, substantially as herein described.

DWIGHT TRACY.
